UNITED STATES PATENT OFFICE.

GEORGE W. LUDLOW, OF ELIZABETH, NEW JERSEY.

IMPROVEMENT IN BOOTS AND SHOES.

Specification forming part of Letters Patent No. 39,156, dated July 7, 1863.

To all whom it may concern:

Be it known that I, GEORGE W. LUDLOW, of Elizabeth, in the county of Union and State of New Jersey, have invented a new and useful Improvement in Boots and Shoes; and I do hereby declare that the following is a full, clear, and exact description of the same, reference being had to the accompanying drawings, forming a part of this specification, in which—

Figure 1 represents a sectional side elevation of my invention. Fig. 2 is a rear elevation of the same.

Similar letters of reference indicate corresponding parts in the two figures.

This invention consists in the application of a flat spring of steel or other suitable material to the back seam of a boot or shoe in such a manner that by the action of said spring the ankle is braced or supported, and, furthermore, the wrinkling and creasing of those parts contiguous to the back seam is prevented, and a shoe is produced which will fit neatly and symmetrically to the foot, and the operation of putting on the shoe is facilitated.

To enable others skilled in the art to fully understand and construct my invention, I will proceed to describe it.

A represents a shoe made of leather or any other suitable material, and of that class generally known by the term of "balmoral" boots. My invention is not confined, however, to this particular class of boots or shoes, and I have only represented a shoe of this kind because it is best adapted to give an illustration of the value of my improvement. In the back seam, *a*, of this shoe I insert a

spring, *b*, made of a flat strip of steel or any other suitable material. This spring extends from the heel *c* up to the top edge of the shoe, and it is fastened by means of clasps *d*, which pass through slots in the spring and through the leather, and are bent up tight on the inside, or any other fastening may be used. The spring may be held at the bottom by extending it between the heel and inner sole of the shoe, or it may terminate at the upper edge of the heel and be fastened in any desirable manner. When the foot is introduced into the shoe, the spring *b* will adapt itself to its shape and support the ankle, and particularly when the shoe is laced up the spring will be drawn up tight to that part of the foot above the heel, and it will not only serve as a support, but it will also prevent those parts of the shoe contiguous to the back seam from wrinkling, and a symmetrically-fitting shoe will be produced. The spring also acts as a horn in putting on the shoe. The back seam is rendered stiff and prevented from breaking down under the foot, and consequently the foot will slip right in with the greatest ease and facility.

What I claim as new, and desire to secure by Letters Patent, is—

The application of a spring, *b*, to the back seam of a boot or shoe, in the manner and for the purpose substantially as shown and described.

GEORGE W. LUDLOW.
